(57) **CLAIM**

The ornamental design for a cosmetics brush, as shown and described.

DESCRIPTION

FIG. 1 is a top, front and right-side perspective view of a cosmetics brush shown in a closed configuration.

FIG. 2 is an enlarged front elevation view thereof.

FIG. 3 is an enlarged rear elevation view thereof.

FIG. 4 is a right-side elevation view thereof.

FIG. 5 is a left-side elevation view thereof.

FIG. 6 is a top plan view thereof.

FIG. 7 is a bottom plan view thereof.

FIG. 8 is a top, front and right-side perspective view of the cosmetics brush shown in a fully-open configuration.

FIG. 9 is an enlarged front elevation view thereof.

FIG. 10 is an enlarged rear elevation view thereof.

FIG. 11 is a right-side elevation view thereof.

FIG. 12 is a left-side elevation view thereof.

FIG. 13 is a top plan view thereof.

FIG. 14 is a bottom plan view thereof.

FIG. 15 is a top plan view of the cosmetics brush shown in a partially-open configuration; and,

FIG. 16 is a bottom plan view thereof.

The bristles, pin extensions and pin apertures delineated in broken lines are environment and form no part of the claimed design.
